T. H. RICHARDSON.
CLEANING APPARATUS.
APPLICATION FILED JUNE 14, 1921.

1,393,641.

Patented Oct. 11, 1921.

FIG. 1.

UNITED STATES PATENT OFFICE.

THOMAS H. RICHARDSON, OF LEXINGTON, NORTH CAROLINA.

CLEANING APPARATUS.

1,393,641.

Specification of Letters Patent.

Patented Oct. 11, 1921.

Application filed June 14, 1921. Serial No. 477,468.

To all whom it may concern:

Be it known that I, THOMAS H. RICHARDSON, a citizen of the United States of America, residing at Lexington, in the county of Davidson and State of North Carolina, have invented certain new and useful Improvements in Cleaning Apparatus of which the following is a specification.

- 10 This invention relates to certain new and useful improvements in cleaning apparatus and has particular reference to a machine designed for either washing or dry cleaning clothes.
- 15 This application is a continuation in so far as disclosed in application filed by me on February 6, 1918, Serial Number 215,628 and application filed November 28, 1919, Serial Number 341,193, and embodies improvements in the art thereover.

20 The primary object of the present invention has reference to clothes cleaning apparatus wherein a tank incloses a perforated reciprocating tumbler with power devices 25 associated with the tumbler for operating the same.

25 A further object of the invention is to provide a clothes cleaning device wherein a reciprocating tumbler arranged with a tank 30 has power devices adjustably connected thereto for changing the range of reciprocations of the tumbler.

35 A further object of the invention has reference to the idea of washing or cleaning clothes in boiling gasoline or like material wherein a tumbler containing the clothes is movably mounted within a tank having a false bottom with a steam heated compartment arranged beneath the false bottom to 40 cause the heating and boiling of the gasoline within the tank. With the above general objects in view and others that will become apparent as the nature of the invention is better understood, the invention consists in the novel form, combination and arrangement of parts hereinafter more fully described in connection with accompanying drawings and in which like reference characters indicate corresponding parts 45 throughout the several views.

In the drawing,

Figure 1 is a vertical sectional view of a clothes cleaning device constructed in accordance with the present invention showing

the operating devices for the tumbler supported on the cover of the tank.

Fig. 2 is a top plan view of the same, Fig. 3 is a side elevational view, partly in section showing the connection between the power devices and the reciprocating tumbler.

Fig. 4 is a horizontal sectional view taken on line IV—IV of Fig. 3 showing the upper end of the tumbler with the swinging closure therefor.

Fig. 5 is a detail sectional view showing the operative connection between the power disk and the cross head carried by a rod secured to the tumbler,

Fig. 6 is a detail sectional view taken on line VI—VI of Fig. 1 showing the block for operating the tumbler cross head adjustably connected to the power disk and

Fig. 7 is a detail sectional view taken on line VII—VII of Fig. 5 showing the cross head secured to the perpendicular rod of the tumbler.

Referring more in detail to the accompanying drawing, there is illustrated a tank 1 having a bottom wall 2 mounted on supporting feet 3 and a rigid cover part 4 hinged as at 5 to a swinging section 6 as clearly shown in Figs. 2 and 3 to permit the tank 1 to be filled with a cleaning fluid such as gasoline or the like. A concaved false bottom 7 is disposed within the tank adjacent the bottom 2 to provide an intervening steam heating chamber 8.

The steam supplying mechanism for the compartment or chamber 8 embodies a steam line pipe 9 connected to a suitable source of supply, not entering into the invention, having, as illustrated in Fig. 1, a short pipe connection 10 with one side of the tank 1 for delivering steam to the chamber 8, the pipe 9 section 10 having a controlling valve 11 therein for regulating the supply of steam to the chamber 8. A branch pipe 12 communicating with the steam line 9 and under control of the hand valve 13 that is positioned adjacent the hand valve 11, has provided therein a check valve 14 adjacent its opposite end, and its point of connection with the pipe section 15. A pipe 16 connected to the tank 1 and in communication with the chamber 8 at a point opposite the pipe section 10 is in communication with the pipe 15, and has a check valve 17 there-

in to permit steam within the chamber 8 to escape through the pipe 16 by way of the check valve 17, and be prevented from returning to the chamber. It being understood that a series of tanks may be operatively connected, the valve 11 may be closed and the steam in the pipe line 9 shunted through the branch 12, controlled by the hand valve 13 and check valve 14 for delivery to the pipe 15 that communicates with an adjacent tank, the tank as illustrated being thereby shut off from communication with the pipe line 9. When steam in the pipe line 9 flows directly into the chamber 8, the hand valve 13 is closed and the check valve 14 in the branch 12 will prevent the flow of steam from the pipe sections 15 and 16 into the branch 12.

A tumbler 18 is reciprocably disposed within the tank 1 and embodies a cylindrical casing perforated over the sides and bottom wall thereof as shown in Fig. 1 while the upper wall 19 has a rotatable door section 20 pivoted axially thereof as shown in Fig. 4 to permit clothes or other articles inserted through the open upper end of the tank 1 being received in the tumbler 18.

The supporting and operating devices for the tumbler embody a pair of perpendicular brackets 21 having horizontal extensions 21' at their upper ends through which guide pins 22 are slidably mounted, the lower ends of the pins slidably extending through accommodating openings in the cover 4 of the tank 1. A cross head 23 having an elongated horizontal slot 24 in one face thereof is provided with openings adjacent the ends as shown in Figs. 2 and 5 for the reception of the guiding pins 22 that are anchored to the cross head by set screws 25. A plate 26 secured to the upper wall 19 of the tumbler as shown in Figs. 1, 3, and 4 carries a perpendicular rod 27 that extends through a central opening in the cross head 23 and the cross head and rod 27 are rigidly connected by the set screw 28 as shown in Figs. 5 and 7.

Bearings 29 mounted on the cover 4 of the tank 1 support the power shaft 30 having loose and fixed pulleys 31 and 32 mounted upon the outer end thereof while a power disk 33 is keyed to the inner end, at a point within the brackets 21 and adjacent the rod 27. The disk 33 is provided with a radial slot 34 shown in Figs. 1, 5, and 6, the opposite walls adjacent the outer face of the disk being slightly beveled as illustrated. The connection between the disk 33 and the cross head 23 embodies a screw 35 having a pin 36 upon one end thereof engaging with a squared nut 37 mounted on the screw with the shoulder of the screw pin engaging the nut to cause the beveled walls thereof to engage the beveled walls of the slot 34, a split washer 38 and a nut 39 being mounted on the threaded end of the screw 25 at the

opposite side of the disk for clamping the screw and pin 36 in adjusted positions in the slot 34. The pin 36 has the outer end thereof freely extending into the slot 24 of the cross head 23.

In the operation of the device, the shaft 30 being driven by the pulley 32 for rotating the disk 33, the pin 36 eccentrically connected to the disk and freely working in the slot 24 of the cross head will cause a vertical reciprocatory movement of the cross head when said disk is rotated with the pin 36 ascribing a circular motion and sliding in the slot 24. The tumbler 18 being connected to the cross head 23 by the rod and screw 27 and 28, said tumbler is caused to reciprocate with the cross head when the disk 33 is rotated. To vary the length of throw of the tumbler, the screw 35 and pin 36 are adjusted radially of the disk 33, the pin 36 when being positioned adjacent the axis of the disk 33, moving the tumbler only a short distance, while a greater throw of the tumbler is attained when the pin 36 is moved to a position adjacent the outer end of the slot 34. The normal position of the tumbler within the tank is also regulated by the adjusting screw 28 so that the tumbler may have a reciprocatory movement adjacent the false bottom 7 or in proximity of the upper wall 4 of the tank. It is not intended that this invention be limited to the steam pressure employed nor the proportions of the several features of the device, it being understood that the walls of the tank 1 including the false bottom 7 may be of such proportions as to provide for the proper confinement of steam under suitable pressure within the chamber 8 while the gasoline or other cleaning fluid within the tank may be heated to the boiling point. It is also not intended that this application be limited to the character of cleaning fluid employed as gasoline, naptha, or other material may be used with equal efficiency.

While there is herein shown and described the preferred embodiment of the present invention, it is nevertheless to be understood that minor changes may be made in the form, combination and arrangement of parts without departing from the spirit and scope of the invention as claimed.

What is claimed as new is:

1. Clothes cleaning apparatus comprising a tank adapted to contain gasoline and a steam chamber adjacent the lower end thereof, means for supplying steam to said chamber, a perforated tumbler reciprocable in said tank and means for reciprocating said tumbler, said means being adjustable to regulate the length of throw of the tumbler.

2. Clothes cleaning apparatus comprising a tank having a steam chamber adjacent the lower end thereof, means for supplying steam to said chamber, a perforated tumbler

- reciprocable in said tank, a rod connected to the upper end of said tumbler and extending through the upper end of the tank, a cross head adjustably secured to said rod above 5 the tank, a power shaft journaled above the tank, a disk secured to said power shaft, and operative connections between said disk and rod.
3. Clothes cleaning apparatus comprising 10 a tank having a steam chamber adjacent the lower end thereof, means for supplying steam to said chamber, a perforated tumbler reciprocable in said tank, a rod connected to the upper end of said tumbler and extending 15 through the upper end of the tank, a cross head adjustably secured to said rod above the tank, a power shaft journaled above the tank, a disk secured to said power shaft, and operative connections between said disk and 20 rod, said connections including a key adjustably mounted radially of said disk and slidably associated with said cross head.
4. Clothes cleaning apparatus comprising a tank having a steam chamber adjacent the 25 lower end thereof, means for supplying steam to said chamber, a perforated tumbler reciprocable in said tank, a rod connected to the upper end of said tumbler and extending through the upper end of the tank, a cross 30 head adjustably secured to said rod above the tank, a power shaft journaled above the tank, a disk secured to said power shaft, and operative connections between said disk and rod, said connections including a key adjust- 35 ably connected radially to said disk, there being a slot in said cross head for freely receiving said key.
5. Clothes cleaning apparatus comprising a tank having a steam chamber adjacent the 40 lower end thereof, means for supplying steam to said chamber, a perforated tumbler reciprocable in said tank, a rod connected to the upper end of said tumbler and extending through the upper end of the tank, a cross 45 head adjustably secured to said rod above the tank, a power shaft journaled above the tank, a disk secured to said power shaft, and operative connections between said disk and rod, said connections including a key adjust- 50 ably connected radially to said disk, there being a slot in said cross head for freely
- receiving said key, guide brackets supported on said tank and guide pins secured to said cross head and slidably associated with said brackets and tank. 55
6. Clothes cleaning apparatus comprising a tank having a steam chamber adjacent the lower end thereof, steam supply means for said chamber, a perforated tumbler reciprocably mounted in said tank, a power shaft 60 rotatably supported on said tank, a disk secured to said power shaft, there being a radial slot in said disk, a key adjustably mounted in said slot, a perpendicular rod carried by said tumbler and extending 65 through the upper end of the tank, a cross head connected to said rod above the tank, said cross head having a slot in the face thereof adjacent the disk for the sliding reception of said pin whereby said rod, cross 70 head and tumbler are reciprocated upon rotation of said disk.
7. Clothes cleaning apparatus comprising a tank having a steam chamber adjacent the lower end thereof, steam supply means for 75 said chamber, a perforated tumbler reciprocably mounted in said tank, a power shaft rotatably supported on said tank, a disk secured to said power shaft, there being a radial slot in said disk, a key adjustably 80 mounted in said slot, a perpendicular rod carried by said tumbler and extending through the upper end of the tank, a cross head connected to said rod above the tank, said cross head having a slot in the face 85 thereof adjacent the disk for the sliding reception of said pin whereby said rod, cross head and tumbler are reciprocated upon rotation of said disk, and independent closures for the upper ends of the tank and 90 tumbler.
8. Clothes cleaning apparatus comprising a tank having a steam chamber adjacent the lower end thereof, steam supply means for said chamber, a perforated tumbler reciprocably mounted in said tank, and adjustable power devices associated with said tumbler 95 for varying the length of reciprocating movements thereof.

In testimony whereof I affix my signature. 100

THOMAS H. RICHARDSON.
